SAFETY CONTROL SWITCH

William L. Callender, 3836 Birchwood Road,
Falls Church, Va. 22041

Filed June 17, 1966, Ser. No. 2,714

Term of patent 14 years

(Cl. D26—13)

FIG. 1.

FIG. 2.

FIG. 3.

FIGURE 1 is a front view of my safety control switch.
FIGURE 2 is a side view of the design shown in FIGURE 1.

FIGURE 3 is a perspective view of my safety control switch design.

The dominant features of the design reside in the portions shown in full line in the drawing.

I claim:

The ornamental design for a safety control switch, as shown and described.
